UNITED STATES PATENT OFFICE.

CHARLES E. CAMPBELL, OF WOODHAVEN, NEW YORK.

WRAPPING MACHINE.

Application filed June 20, 1919. Serial No. 305,568.

To all whom it may concern:

Be it known that I, CHARLES E. CAMPBELL, a citizen of the United States, and a resident of Woodhaven, Long Island, county of 5 Queens, State of New York, have invented certain new and useful Improvements in Wrapping Machines, of which the following is a specification.

The present invention relates to improvements in wrapping machines, and particularly a machine of this character adapted to automatically and continuously fold and paste wrappers about an article of rectangular shape, as for instance, tin boxes such as 10 are used for containing sardines. It is an object of the invention to provide a machine of this character which may be operated with relative speed, will require only the services of one attendant, and will carry out 15 the wrapping operation in a neat uniform manner.

With these and other objects in view, an embodiment of my invention is shown in the accompanying drawings and this embodiment will be hereinafter more fully described with reference thereto and the invention will be finally pointed out in the claims.

In the accompanying drawings:

Figure 1 is a plan view of the machine 30 according to one embodiment of my invention disclosed by way of example herein;

Figure 2 is a side elevation thereof;

Figure 3 is a transverse sectional view taken along the line 3—3 of Figure 2;

Figure 4 is a detail view showing the tucking arms and the operating mechanism therefor;

Figure 5 is an enlarged detail vertical sectional view of the stack of wrappers and 40 the gripping and wrapper delivering means;

Figure 6 is a detail view of one of the wrapper raising members retracted;

Figure 7 is a similar view showing the same projected;

Figure 8 is a perspective view of one of the carriers for moving the can and wrapper from one operative mechanism to another;

Figure 9 is a longitudinal vertical sectional view of one of the carriers;

Figure 10 is a perspective view showing the wrapper and the can to be wrapped placed therein;

Figure 11 is a vertical sectional view of 55 the table and adjacent parts supporting the

wrapper and can in the position indicated in Figure 10;

Figure 12 shows the wrapper folded upwardly at the sides of the can;

Figure 13 shows the position of the table 60 to bring about this step in the wrapping process;

Figure 14 shows one side of the wrapper folded down upon the top of the can;

Figure 15 shows the carrier in position to 65 bring about this step;

Figure 16 shows the other side of the wrapper folded down upon the upper side of the can and pasted;

Figure 17 shows the position of the can 70 and wrapper under the pressure rollers for bringing about the step of the wrapping process shown in Figure 16;

Figure 18 shows the upper portion of the projecting ends of the wrapper folded down;

Figure 19 shows the folding blades for performing this step, and their position relatively to the can and wrapper;

Figure 20 shows the projecting side portions tucked in upon the folded down upper 80 portions;

Figure 21 shows the tucking arms and their position relatively to the can and wrapper; the dotted lines showing the raised position, while the full lines show the lowered position;

Figure 22 shows the projecting lower portions folded upwardly upon the ends of the box and pasted, this being the final step;

Figure 23 shows the depressible supporting rollers adapted to perform this final step in the process;

Fig. 24 is a vertical section through the entire machine taken at right angles to the showing in Fig. 3.

Fig. 25 is a detail enlarged side elevation taken substantially at right angles to Fig. 3 of the wrapper gripping and delivering and adjacent means, and

Fig. 26 is a top plan view of the same.

Similar reference characters indicate corresponding parts throughout the several figures of the drawings.

Referring to the drawings, the main frame of the machine comprises a pair of upright 105 side supports or standards 30 and 31 connected by suitable bracing rods 32 and provided at one end with extension members 33 and 34 secured thereto and having raised platforms 35 and 36 formed thereon, the said 110

members being connected by a bracing rod 37.

Upon the upper sides of the supports 30 and 31, there are secured longitudinal trackways 38 and 39 having an enlarged longitudinally channeled portion projecting inwardly of the supports, and a flat longitudinal shelf portion resting on and secured to the supports. Within the channels of the 10 trackways, there are reciprocatingly mounted slide bars 40 and 41 having antifriction rollers 42 disposed within the channel, and adapted, as will hereinafter more fully be pointed out, to carry the wrapper and can 15 transference means to and fro.

The wrappers A are supported upon a table 43 disposed at the upper end of a screw 44 movable through the threaded bore of a worm gear 45, rotatably disposed in the 20 bearing portion 46 of a crosspiece 47, connected at its ends to the supports 30 and 31. A transverse shaft 48 is journaled in brackets 49 and 50 formed upon the crosspiece 47 and in bearings 51 and 52 formed in the 25 supports 30 and 31, and having mounted thereon, a worm meshing with the gear 45 and adapted upon being turned to slowly turn the said gear and thereby gradually and slowly cause the table to be raised as the 30 wrappers are removed therefrom, the successive upward movements of the table being equal to the thickness of one wrapper. Upon one end of the shaft 48, there is provided a ratchet gear 53, and at the side of 35 the same, an arm 54 provided with a spring pressed pawl 54^a engaging the ratchet, the end of the arm being connected by a connecting rod 55 to a crank arm 56 provided upon the end of a shaft 57 journaled in the 40 supports 30 and 31, and adapted to continuously rotate from the transmission means as will hereinafter more fully appear.

The stack of wrappers is guided and confined at its forward side by means of bars 45 58 and 59 supported at their upper ends upon a transverse shaft 60 journaled in the supports 30 and 31 and disposed below the upper end of the stack and provided at their lower end with forked portions 61 engaging 50 over the shaft 48. At its rearward side the stack is engaged by bars 62 supported at their upper ends in brackets 63 mounted upon a shaft 64, and fixed against rotation by means of set screws 65, the ends of the 55 said shaft being adjustably engaged in slots 66 and 67 provided respectively in the extension members 33 and 34. There are also mounted upon the shaft 64, brackets 68, in the cylindrical portions 69 of which there 60 are disposed vertically arranged pressure members 70, the lower end thereof being capped with rubber or other suitable frictional material as at 71, springs 72 disposed between the lower capped ends of the brackets 65 yieldingingly engaging the members with

the uppermost wrapper adjacent its rearward edge. The table 43 is provided with slots 73 which embrace the bars 62, and at their lower ends the said bars are engaged at their forward sides by a transverse rod 74 70 having its ends disposed in slots 75 of extension brackets 47^a supported upon the crosspiece 47, adjustable set screws 75^a holding the said rod in engagement with the bars.

At the upper side of the members 38 and 39 there are mounted standards 76 and 77 having tables 78 and 79 provided thereon and upon which there is supported a transverse platform 80. A similar platform 81 is supported between the tables 35 and 36, 80 and a third and longitudinally disposed platform 82 is supported at its ends upon the tables 35 and 78. Upon the respective platforms 80, 81 and 82, there are mounted paste boxes 83, 84 and 85. The platform 81 is adjustable by means of slots 81^a and bolts 81^b, while the platform 82 is similarly adjustable by slots 82^a and 82^b to permit of the paste boxes being adjusted to different sized 85 wrappers.

The box 83 comprises side members 86 and 87 having bearing portions 88 at their forward ends in which are journaled the respective shafts 89 and 90 of a paste feed roller 91, and a rotary paste transference member consisting of an arm 90^a fixed to the shaft 90 and carrying a flexible brush member 90^b of rubber or other suitable material and adapted upon rotation to successively receive paste from the roller 91 and impart the same to the edge of the paper as at a Figure 1. A gear 92 is provided upon the shaft 89 which meshes with and drives a smaller gear 93 provided upon the shaft 90, the shaft 89 extending from the paste box through a supporting bearing bracket 94 mounted upon the table 79, the said shaft being provided at its end with a sprocket 95 driven by a suitable chain connection hereinafter referred to, from the transmission means. The floor 96 of the paste box is in yielding engagement at its forward end with the surface of the roller 91 and may be regulated relatively to the surface of the said roller by means of a plurality of elongated set screws 97 bearing at their forward ends upon pivotally mounted shoes 98 in turn to bear upon and move pins 99 engaging the flexible end of the floor. The flow of paste to the surface of the roller 91 may thereby be accurately regulated both as to thickness and location.

The paste box 84 is similar in construction to the box 83, the driving shaft 100 carrying the roller 101 and the gear 102 which meshes with and drives the smaller gear 103 upon the shaft 104 carrying the rotatable paste transference member 105 extending through a supporting bearing bracket 106 supported upon the table 36 105 110 115 120 125 130

and terminating in a sprocket gear 107 driven by suitable connections hereinafter more fully referred to from the transmission means. The member 105 is adapted to impart the paste to the edge of the wrapper as at *b*.

The paste box 85 is substantially wider than the boxes 83 and 84 and is adapted to impart a relatively long strip of paste as at *c* to one end of the wrapper. The shaft 108 upon which the roller 109 is mounted, is provided with a gear 110 meshing with the smaller gear 111 provided upon the shaft 112 of the paste transference member 113, and upon the shaft 108 there is also provided a beveled gear 114 which meshes with a beveled pinion 115 mounted upon one end of a shaft 116 journaled in a bracket 117 provided upon the side of the box 85 and provided at its other end with a sprocket gear 118 driven by a chain connection hereinafter referred to from the transmission means.

At the forward ends of the slide bars 40 and 41, there are mounted journal boxes 119 each having a pair of sockets in which are respectively mounted the ends of a non-rotatable shaft 120 and a rotatable shaft 121. Upon the non-rotatable shaft 120 there is mounted a pair of gripping fingers 122 extending beneath and adapted to cooperate with a pair of gripping fingers 123 to grip the wrapper in the forwardly moved position of the slide bar as indicated in Figures 1 and 5, the said gripping fingers being preferably capped at their ends with rubber or the like. An arm 124 carrying a roller 125 is provided upon the shaft 121 and engages at the ends of the forward and rearward movement of the slide bars, the respective tripping cams 126 and 127 to cause the fingers to grip and release the wrapper, the fingers being retained in their moved positions by means of leaf springs 128 secured to collars 129 on the non-rotatable shaft 120, and bearing upon fingers 130 provided upon collars 131 mounted on the rotatable shaft 121, the springs acting upon the fingers at either side of the dead center formed by the axis of rotation of the shaft.

In order to position the wrapper to be properly gripped by the fingers, there are provided at each side of the stack of wrappers upon the frame slideways 132 and 133 angularly disposed and adjustable as to their angle by means of the circumferentially slotted base plates 134 secured to the frame by bolts 135 and 136. In the channels 137 and 138 respectively of the slideways there are mounted slide-rods 139 adapted to be reciprocated by crank levers 140 and 141, engaging pins 142 provided upon the rods at their slotted ends 143 and 144, the said levers being pivotally mounted at 146 and 147 upon posts 148 and 149 formed upon the frame and having their short arms connected by

rods 150 and 151 respectively to levers 152 and 153 pivotally mounted at 154 and 155 upon the frame, springs 156 and 157 being connected between the inner arms of the said levers 152 and 153 and the points 158 and 159 secured to the frame, and normally holding the slide-rods in their retracted positions.

Upon the slide bars 40 and 41 there are secured brackets 160 and 161 pivotally supporting trip fingers 162 and 163, the said fingers having inclined ends and projecting in the path of the inclined ends of the levers 152 and 153 and held against stops 164 and 165 by means of springs 166 and 167. During the rearward movement of the slide bars, the trip fingers 162 and 163 carried thereby pivot during their engagement with the levers 152 and 153 and ride freely over the same. When the slide bars move forward however, the trip fingers are held rigid during engagement with the levers 152 and 153 and cause the same to be swung about their pivots thereby reciprocating the slide-rods 139.

The slide-rods 139 are jointed at 168 (Figures 6 and 7) and during their projecting movement first swing downwardly into engagement with the wrapper and continue moving toward each other in engagement with the wrapper, causing the same to be humped at its intermediate portion. For this purpose a projecting arm 169 is provided upon the forward end of the slideway and engages the under surface of the forward portion of the slide-rods, the said slide-rods having at said under surface an inclined surface 170 which causes the same to be raised and lowered. At the forward end of the rods 139 there are provided caps 180 provided with an inset of rubber or other suitable gripping substances 181 provided with a threaded shank 182 engaging the end of the rod to enable adjustment.

When the wrapper is in its humped position, a pair of spacing fingers 183 and 184 having wedge shaped ends 185 and fixedly mounted upon the transverse rock shaft 60, enter beneath the wrapper and hold the same raised so that it may be gripped at its edge by the gripping fingers 182 and 183. As indicated in Figure 5, the shaft is rocked by means of an arm 187 fixed thereon and provided at its end with a roller 188 engaging a cam 189 provided upon the shaft 57.

At the end of the machine opposed to the stack of wrappers, there is provided an extension frame comprising a pair of tubular standards 190 and 191 having circular bases 192 and 193 and provided with telescoping posts 194 adapted to be fixed in their position by means of set screws 195. Collars 196 and 197 are secured to the posts 194 and longitudinal rods 198 and 199 are screwed thereon at one end as at 200 and at their other ends are screw threaded at 201 and adjustably engaged with a transverse cross-

piece 202 connecting the supports 30 and 31, lock-nuts 203 fixing the position of the said rods. Upon the rods 198 and 199 there are supported in spaced relation, inverted U-shaped supports 204 and 205 carrying a longitudinal platform 206 disposed beneath and supporting the upper part of a feed belt 207 extending over rollers 208 and 209 mounted respectively upon a shaft 210 journaled in the frames 30 and 31, and a shaft 211 journaled in bearings 212 and 213, adjustable longitudinally of the belt to tighten or regulate the same by means of adjustable screw supports 214, mounted in the ends of yoke members 215 and 216 provided at the upper ends of the posts 194. At the sides of the belt there are provided longitudinal guides 217 and 218 between which the can or other articles B to be wrapped are fed, the foremost can being positioned preparatory to being removed by means of yieldable holding fingers 219 and 220.

Upon the slide bars 40 and 41 there are secured upstanding standards 221 and 222 between which there is supported a shaft 223. Upon the shaft 223 there is supported a fixture 224 extending downwardly and provided with a gripping face 225 adapted to engage the can at one side. A bracket 226 is also secured upon the shaft 223 and pivotally supports a lever arm 227 provided at one end with a gripping face 228 adapted to engage the can at the other side thereof from the face 225, and provided at its other end with a roller 229 adapted to respectively engage trip cams 230 and 231 at the ends of its forward and rearward movement to release and grip the cans, a spring 232 adapted to hold the lever in gripping engagement with the can. When the arm is moved as indicated in Figure 3 to release the can by engagement with the cam 230, a snap spring 233 engages beneath the arm and holds the same in its disengaged position until the roller engages the cam 231 whereupon the force of the snap spring 233 is overcome and the arm is caused to grip the can. In operation the feeding of the can and wrapper into superimposed relation, is as follows:

The gripping fingers 122 and 123 upon rearward reciprocation of the slide bars 40 and 41, remove a wrapper from the stack and deposit it upon the table 234 against limiting stops 235 and 236. Alternately with the gripping of the wrapper, the can gripping arms 224 and 227 grip the forward can and upon forward reciprocation of the slide bars, carry the same over the previously deposited wrapper and drop it thereon as indicated in Figures 2 and 3, the forward movement of the slide bars overcoming the holding force of the holding fingers 219 and 220.

65 The slide bars 40 and 41 are reciprocated

by means of levers 237 and 238 connected to the rear ends of the said bars by links 239 and 240 and mounted upon a shaft 241 journaled in supports 242 and 243 secured to the ends of the supporting frames 30 and 31 and provided at one end with an arm 244, connected by a rod 245 to a crank lever 246 mounted at one end of a shaft 247, the said shaft being provided at its other end with a gear 248, meshing with and driven by a gear 249 mounted on the shaft 250, and which in turn is driven by a pinion gear 251 provided upon a driving shaft 252 which may be connected to any suitable source of motive power.

Upon the shaft 250 there is provided a sprocket gear 253 connected by a sprocket chain 255 to a sprocket gear 256 provided upon a shaft 257 journaled in the supports 30 and 31, and provided with a gear 258 meshing with and driving the gear 259 of a transverse shaft 260 also journaled in the supports 30 and 31 and provided with sprocket gears 261 and 262, the former being connected by a sprocket chain 263 to the sprocket gear 118 for driving the pasting means adapted to impart the strip of paste c to the wrapper, while the latter is connected by a sprocket chain 264 to the sprocket gear 95 for driving the pasting means 83 for imparting the paste as at a to the wrapper. Upon the shaft 260 there is provided a sprocket gear 265 connected by a chain 266 to the sprocket 107 for driving the pasting means 84 for imparting the paste as at b to the wrapper. The shaft 57 is driven by means of a sprocket gear 171 upon the shaft 260 connected by a chain 172 to a sprocket gear 173 mounted on the shaft 57.

The shaft 250 is provided with a sprocket gear 267 connected by a chain 268 to a sprocket gear 269 provided upon a shaft 270 journaled in the supports 30 and 31 and having thereon a pinion 271 meshing with and driving a gear 272 provided upon the shaft 210 for driving the feed belt 207.

Disposed transversely beneath the frame and at each side of the table 234 there are provided two continuous driving chains 273 and 274 extending over sprocket wheels 275 provided upon shafts 276 and 277 and 278 and 279 journaled in bearing brackets 280 and 281 mounted upon the respective supports 30 and 31, the said chains passing through openings 282 and 283 and 284 and 285 formed in said supports.

The shaft 277 is provided at one end with a beveled pinion 286 meshing with a beveled gear 287 mounted at one end of a shaft 288 journaled in the supports 30 and 31 and provided at its other end with a gear 289 meshing with the gear 249 of the shaft 250 and adapted to be driven thereby from the driving pinion 251 to cause the chain to travel in the direction of the arrows (Figure 3)

The table 234 has a longitudinal opening 290 therein provided with downwardly bent side portions 291 and 292, and slightly wider than the can or other article to be wrapped, and within this opening there is disposed a vertically movable platform 293 supported upon four posts 294, 295, 296 and 297 slideable in vertical passages 298 formed in bearing portions 299 of crosspieces 300 and 301 extending between the supports 30 and 31, the downwardly depending portions of the said posts having springs 302 coiled thereon, and bearing at their ends upon the under sides of the portions 299 and upon collars 303 provided on the ends of the said posts.

The crosspieces 300 and 301 are respectively provided with longitudinally disposed bearings 304 and 305 in which is journaled a shaft 306 adapted to be rotated from the sprocket wheel shaft 278 by sprockets 307 and 308 respectively provided on the said shafts and a continuous chain connection 309, a cam 310 being provided on the shaft 306 engaging a roller 311 mounted upon the under side of the platform 293 and adapted to raise and lower the said platform, the cam being of such design that the platform is in its raised position during a quarter of a revolution of the shaft 306 and in its lowered position during a quarter of a revolution.

Beneath the table 234 there are mounted upon supports 312 and 313, and between the chains 273 and 274, supporting shelves 314 and 315 disposed at each side of an opening 316 into which the platform 293 descends with its upper surface flush with the upper surface of the said shelves, this movement causing the end portions of the wrapper A to be bent upwardly at each side of the can B, indicated in Figure 13.

Supported upon and extending between the chains 273 and 274, there are provided a series of carriers (Figures 8 and 9), each of the said carriers consisting of a crossbar 317 mounted at its ends upon blocks 318 and 319 secured respectively to one of the links of the chains, the said bar being provided with a forwardly projecting central portion 320 in which there is rotatably mounted a pusher roller 321. A plate 322 is disposed upon the upper side of the bar 317 being provided with a raised forward end portion 323 extending above and having its forward edge in front of the roller 321 in one position thereof. The plate 322 is provided with slots 324 and 325 engaged by guide pins 326 provided on the bar 317, and at its rear end is bent downwardly as at 327, the said portion 327 being held in engagement with cam fingers 328 provided on the rock shaft 329 journaled in bearings 330 of the bar 317 by a spring 331 extending between a lug 332 at the under side of the plate and the said downwardly bent portion. Upon one end

of the shaft 329 there is provided a trip lever 333 which as its upper arm comes into engagement with a trip pin 334, moves the cam 330 into the downwardly extending position shown in Figures 3 and 9 in which 70 position the end of the plate 322 extends beyond the periphery of the roller 321, and which when its lower arm engages a trip pin 334^a moves the cam into its raised position (Figure 3) retracting the plate 322 so that 75 its forward edge is rearwardly of the periphery of the roller for a purpose which will be presently more fully pointed out.

As the carrier comes into contact with the can disposed upon the platform 293 in its lowered position, the upturned wrapper at one side is engaged by the projected portion 323 of the plate 322 and is thereby folded over the top of the can as indicated in Figure 15 and as the can is moved on to the 85 shelf 314 by the movement of the carrier, the downwardly bent portion 291 of the table 234 folds down the upturned side upon the top of the box in superimposed relation to the other folded down portion of the 90 wrapper.

At the under side of the table 234 there are provided upon brackets 335 and 336 a pair of swinging arms 337 and 338 carrying pressure rollers 339 and 340 having springs 95 341 and 342 bearing thereon and beneath which the can passes, the pressure of the rollers causing the upper folded over portion of the wrapper to be pasted down upon the lower folded over portion as indicated in 100 Figure 17.

A pair of supports 343 and 344 are secured to the ends of the brackets 280, being braced at their outer ends by rods 345 and 346 and upon their upper sides there are mounted standards 347 and 348. Upon the inner sides of the said standards 347 and 348 there are provided brackets 349 and 350 in which are mounted pivoted frames 351 and 352, rollers 353 and 354 being suitably mounted respectively in the outer ends of the frames while their inner ends are yieldably held against stops 355 and 356 by springs 357 and 358, the outer roller end adapted to be swung downwardly when pressure is applied thereto. The surfaces of the said rollers are in line with the upper surface of the shelf 314, while their peripheries extend within the end extremities of the can to support the same thereon.

An extensible shelf 359 is provided in continuation of the shelf 314 being slidably mounted upon a support 360 secured to the support 30, a slot 361 being provided in the said support which is engaged by a guide lug 362 secured to the under side of the shelf, a spring 363 connected to the said lug normally holding the said shelf in its rearward position with one end abutting the end of the shelf 314 while its other end terminates above

the axis of the sprocket shaft 276. As the can reaches a position on the shelf 359 with its end extending over the edge thereof as shown in Figure 8, a lug 364 on the under 5 side thereof is engaged by a finger 365 carried by the chain and thereupon the shelf is moved forwardly with the chain, depositing the can upon the rollers 353 and 354, the shelf being thereupon released so that it 10 returns to its retracted position as the finger 365 passes over the center of the shaft 276. At this point the can is in the position indicated in dotted lines in Figure 3, the plate 322 being retracted as above pointed out to 15 free the same from the upper surface of the can.

As the carrier turns down after passing the center of the sprocket shaft, the continued engagement of the roller with the end 20 of the cam moving in an arc, forces the can to be moved entirely upon the rollers 353 and 354 from the dotted line to the full line position (Figure 3).

A pair of supports 366 and 367 are 25 mounted upon the supports 30 and 31 in which is journaled a shaft 368 having mounted thereon a pair of arms 369 and 370 provided at their ends with folding blades 371 and 372. Upon one end of the shaft 368 30 there is provided a lever 373 pivotally connected to the end of a bar 374 extending through an opening 30* in the support 30, and provided at its other end with an elongated slot 375 engaging the shaft 306 and 35 provided at each end of the said slot with rollers 376 and 377 riding upon a cam 378 provided on the said shaft, rotation of the said cam adapted through the lever and bar connection to swing the arms 369 and 370 40 causing the blades to engage the upper projecting portions of the wrapper and fold the same down upon the ends of the can as shown in Figure 19.

Two shafts 379 and 380 are journaled in 45 the standards 347 and 348 and are provided with pairs of tucker arms 381, 382, 383 and 384 disposed at the outer sides of the blades 371 and 372. Upon the ends of the said shafts there are provided intermeshing 50 gears 385 and 386, and upon the extended end of the shaft 380 there is mounted a lever 387 (Figure 4) pivotally connected to the end of a bar 388, the said bar being provided at its other end with a slot 389 engaging a stud 55 shaft 390 provided upon the support 344, rollers 391 and 392 being provided at the ends of the said slot which ride upon a cam 393 provided upon the said stud shaft, the shaft being rotated by means of a gear 394 provided thereon and meshing with a pinion 395 provided upon the end of the sprocket shaft 276. As the said arms are swung toward each other from the dotted line position (Figure 21) to the full line position, 60 their ends engage the projecting side por-

tions of the wrapper and fold the same inwardly upon the ends of the can in superimposed relation to the folded down end portions.

A block 396 is mounted upon the rods 345 70 and 346 and is provided with a passage 396* in which there is slidably mounted a vertically disposed post 397 having a horizontally bent upper portion 398 provided at its end with a plunger head 399 having spaced 75 contact lugs 399* adapted to firmly engage the upper side of the can as the post descends. Reciprocation of the post is brought about by means of a link 400 connecting its lower end with an arm 401 provided upon a 80 rock shaft 402 journaled in the supports 343 and 344, the said rock shaft 402 being provided at one end with a lever 403 pivotally connected to the end of a bar 404, the other end of the said bar being provided with a 85 slot 405 engaging a stud shaft 406 provided upon the support 343, rollers 407 and 408 being provided at the ends of the said slot which ride upon a cam 409 provided on the shaft, the said shaft being rotated by a gear 90 410 provided thereon and meshing with a pinion 411 provided on the end of the sprocket shaft 276.

As the plunger head descends, it forces the can downwardly between the rollers 353 and 354 at the same time folding the lower projecting portion of the wrapper upwardly and pasting the same upon the folded upper and side portions as indicated in Figure 23. As the can passes from between the rollers, it 100 may drop upon a suitable chute (not shown) to convey the same away from the machine.

My improvements provide a machine which may be operated with relatively great speed in which cans or other suitable articles 105 may be wrapped in a clean, neat uniform manner. The imparting of the paste to the wrapper and the handling of the pasted wrapper in connection with the can or other article is such that the working parts of the machine will not come in contact with the paste and therefore will not impair the efficiency thereof by becoming gummed with the paste.

I have illustrated and described a preferred and satisfactory embodiment of my invention but it is obvious that changes may be made therein within the spirit and scope thereof as defined in the appended claims.

I claim:

1. In a wrapping machine, a wrapper holder, feeding means adapted to singly remove wrappers from said wrapper holder and deposit said wrappers at a point removed from said wrapper holder, a support for said wrappers, means adapted to intermittently raise said support after each removal of said wrappers to maintain the uppermost wrappers in a predetermined plane, a plurality of paste applying means dis-

- posed above said wrapper holder, each comprising a reservoir, a paste roller adapted to receive paste therefrom, means adapted to constantly rotate said paste roller, a rotary 5 paste applying brush member adapted to receive paste from said paste roller and apply said paste to successive wrappers at predetermined portions thereof prior to their removal from said wrapper holder, means 10 adapted to deposit said articles to be wrapped in superimposed relation to said deposited wrappers, and means adapted to cause said wrappers to be wrapped and pasted about said articles.
- 15 2. In a wrapping machine, a wrapper holder, feeding means adapted to singly remove wrappers from said wrapper holder and deposit said wrappers at a point removed from said wrapper holder, a support 20 for said wrappers, means adapted to intermittently raise said support after each removal of said wrappers to maintain the uppermost wrappers in a predetermined plane, a plurality of paste applying means dis-
- 25 posed above said wrapper holder and adapted to apply paste to said uppermost wrappers at predetermined portions thereof prior to their removal from said wrapper holder, means adapted to permit adjustment of said 30 paste applying means to vary the point-of application of said paste, means adapted to deposit said articles to be wrapped in superimposed relation to said deposited wrappers, and means adapted to cause said wrappers 35 to be wrapped about said articles.
3. In a wrapping machine, a wrapper holder, positioning means removed from said wrapper holder adapted to position the articles to be wrapped, reciprocating means 40 operable intermediate said wrapper holder and said positioning means adapted to alternately receive said wrappers and said articles in superimposed relation preparatory to being wrapped, means adapted to deposit said 45 wrappers and said articles in superimposed relation, a reciprocating table adapted to support said wrappers and said articles and adapted to move said wrappers and said articles to a plane below said intermediate 50 means, means adapted to fold the end portions of said wrapper upwardly about the sides of said articles during the movement of said wrappers and said articles to said lower plane, conveyor means adapted to 55 convey said wrappers and said articles along said lower plane, conveyor means adapted to fold over one upstanding end of said wrappers upon the tops of said articles, means adapted during conveying of said wrappers and said articles to fold the other upstanding end upon said tops of said articles in superimposed relation to said other folded end, and means adapted to fold said wrappers about the 60 ends of said articles.
4. In a wrapping machine, a wrapper holder, means adapted to apply paste to the wrappers in said wrapper holder at predetermined portions thereof, positioning means removed from said wrapper holder 70 and said positioning means adapted to receive said wrappers and said articles in superimposed relation preparatory to being wrapped, alternately operable reciprocating means operable between said wrapper holder and said positioning means adapted to deposit said wrappers and said articles in superimposed relation, a reciprocating table adapted to support said wrappers and said articles and adapted to move said wrappers and said articles to a plane below said intermediate means, means adapted to fold the end portions of said wrappers upwardly about the sides of said articles during the movement of said wrappers and said articles to said lower plane, conveyor means adapted to convey said wrappers and said articles along said lower plane, means carried by said conveyor means adapted to fold over one upstanding end of said wrappers upon the tops of said articles, means adapted during conveying of said wrappers and said articles to fold the other upstanding end upon the tops of said articles in superimposed relation to said other folded end, and means adapted to fold said wrappers about the ends of said articles.
5. In a wrapping machine, means adapted to successively feed wrappers and articles to be wrapped in superimposed relation, means adapted to fold the end portions of said wrappers upwardly about the sides of said articles, an endless conveyor, pusher means carried thereby adapted to engage said wrappers and articles to convey the same 100 from said means for folding said end portions upwardly, projecting means on said pusher means adapted to engage over the tops of said articles at one side to fold one of said upstanding ends over upon the tops of said articles, a platform adapted to support said wrappers and said articles as they are conveyed, means in the path of said other upstanding end adapted to fold the same over upon the tops of said articles in superimposed relation to said first folded end, supporting means adapted to receive said wrappers and said articles from said conveying means, and folding means adapted to operate in relation to said supporting means to fold said wrappers about the ends of said articles.
6. In a wrapping machine, means adapted to successively feed wrappers and articles to be wrapped in superimposed relation, means adapted to fold the end portions of said wrappers upwardly about the sides of said articles, an endless conveyor movable in one direction in a horizontal plane, guide means adapted to guide said conveyor in a ver-

tical direction from said horizontal plane, pusher means carried by said endless conveyor adapted to engage said wrappers and said articles to convey the same from said 5 means for folding said end portions upwardly, yieldable projecting means on said pusher means adapted to engage over the tops of said articles at one side to fold one of said upstanding ends over upon the tops 10 of said articles, a platform adapted to support said wrappers and said articles as they are conveyed, means in the path of said other upstanding end adapted to fold the same over upon the tops of said articles in 15 superimposed relation to said first folded end, supporting means adapted to receive said wrappers and said articles from said conveying means at the end of the horizontal movement in one direction of said conveying 20 means, means for retracting said yieldable projecting means of said pusher so as to disengage it from the tops of said articles as said pusher means moves with said conveyor from said horizontal to said vertical direction. 25

7. In a wrapping machine, means adapted to successively feed wrappers and articles to be wrapped in superimposed relation, means adapted to fold the end portions of 30 said wrappers upwardly about the sides of said articles, conveyor means adapted to convey said wrappers and said articles from said means for folding said end portions upwardly, means carried by said conveyor 35 means adapted to fold over one upstanding end of said wrappers upon the tops of said articles as it engages said wrappers and said articles, a platform adapted to support said wrappers and said articles as they are conveyed, means in the path of said other upstanding end adapted to fold the same over upon the tops of said articles in superimposed relation to said first folded end, supporting means adapted to receive said wrappers and said articles from said conveyor means, an extensible platform at the end of said first mentioned platform, means on said conveyor adapted to project said extensible platform to move said wrappers and said 40 articles upon said supporting means, and folding means adapted to operate in relation to said supporting means to fold said wrappers about the ends of said articles. 45

8. In a wrapping machine, means adapted to successively feed wrappers and articles in superimposed relation, means adapted to fold the end portions of said wrappers upwardly about the sides of said articles, conveyor means adapted to convey said wrappers and said articles from said means for folding said end portions upwardly, means carried by said conveyor means adapted to fold over one upstanding end of said wrappers upon the tops of said articles as it engages said wrappers and said articles, 55

means in the path of said other upstanding end adapted to fold the same over upon the tops of said articles in superimposed relation to said first folded ends as said wrappers and said articles are conveyed, supporting 70 means adapted to receive said wrappers and said articles from said conveyor means, folding blades adapted to fold the projecting upper side portions of said wrappers upon the ends of said articles, and folding means adapted to operate in relation to said supporting means to fold the end and bottom portions of said projecting sides of said wrappers about the ends of said articles. 75

9. In a wrapping machine, means adapted to successively feed wrappers and articles in superimposed relation, means adapted to fold the end portions of said wrappers upwardly about the sides of said articles, conveyor means adapted to convey said wrappers and said articles from said means for folding said end portions upwardly, means carried by said conveyor means adapted to fold over one upstanding end of said wrappers upon the tops of said articles as it engages said wrappers and said articles, means in the path of said other upstanding end adapted to fold the same over upon the tops of said articles in superimposed relation to said first folded ends as said wrappers and said articles are conveyed, supporting means adapted to receive said wrappers and said articles from said conveyor means, means adapted to fold the projecting upper side portions of said wrappers upon the ends of said articles, swinging arms adapted to fold the projecting ends of said projecting side portions of said wrappers about the ends of said articles, and means adapted to fold the bottom portions of said projecting sides of said wrappers about the ends of said articles. 90

10. In a wrapping machine, means adapted to successively feed wrappers and articles in superimposed relation, means adapted to fold the end portions of said wrappers upwardly about the sides of said articles, conveyor means adapted to convey said wrappers and said articles from said means for folding said end portions upwardly, means carried by said conveyor means adapted to fold over one upstanding end of said wrappers upon the tops of said articles as it engages said wrappers and said articles, means in the path of said other upstanding end adapted to fold the same over upon the tops of said articles in superimposed relation to said first folded ends as said wrappers and said articles are conveyed, supporting means adapted to receive said wrappers and said articles from said conveyor means, said supporting means comprising yieldable rollers adapted to yieldably support said wrappers and said articles at their ends and adapted to have outward movement to permit of the 115

120

125

130

passage of said wrappers and said articles between said rollers, means adapted to fold the projecting upper and end portions of the projecting sides of said wrappers about 5 the ends of said articles, and a plunger adapted to force said wrappers and said articles between said supporting rollers, said last mentioned action adapted to fold the projecting bottom portions of the projecting 10 sides of said wrappers about the ends of said articles.

11. In a wrapping machine, means adapted to successively feed wrappers and articles in superimposed relation, means adapted to apply paste at predetermined portions upon said wrappers, means adapted to fold the end portions of said wrappers upwardly about the sides of said articles, conveyor means adapted to convey said wrappers and said articles from said means for folding said end portions upwardly, means carried by said conveyor means adapted to fold over one upstanding end of said wrappers upon the tops of said articles as it engages said wrappers and said articles, means in the path of said other upstanding end adapted to fold the same over upon the tops of said articles in superimposed relation to said first folded ends as said wrappers and said articles are conveyed, supporting means adapted to receive said wrappers and said articles from said conveyor means, said supporting means comprising yieldable rollers adapted to yieldably support said wrappers and said articles at their ends and adapted to have outward movement to permit the passage of said wrappers and said articles between said rollers, means adapted to fold the projecting upper and end portions of the projecting sides of said wrappers about the ends of said articles, and a plunger adapted to force said wrappers and said articles between said supporting rollers, said

last mentioned action adapted to fold and paste the projecting bottom portions of the 45 projecting sides of said wrappers about the ends of said articles.

12. In a wrapping machine, means adapted to successively feed wrappers and articles in superimposed relation, means adapted to fold the end portions of said wrappers upwardly about the sides of said articles, conveyor means adapted to convey said wrappers and said articles from said means for folding said end portions upwardly, means carried by said conveyor means adapted to fold over one upstanding end of said wrappers upon the tops of said articles as it engages said wrappers and said articles, means in the path of said other upstanding end adapted to fold the same over upon the tops of said articles in superimposed relation to said first folded ends as said wrappers and said articles are conveyed, supporting means adapted to receive said wrappers and said articles from said conveyor means, said supporting means comprising compressible rollers adapted to support the ends of said wrappers and said articles and adapted to be swung downwardly in diverging arcs to permit of the passage of said wrappers and said articles therethrough, means adapted to fold the projecting upper and end portions of the projecting sides of said wrappers about the ends of said articles, and a plunger adapted to force said wrappers and said articles between said supporting rollers, said last mentioned action adapted to fold the projecting bottom portions of the projecting sides of said wrappers about the ends of said articles.

In testimony that I claim the foregoing as my invention, I have signed my name hereunder.

CHARLES E. CAMPBELL.
